ATTORNEY.

UNITED STATES PATENT OFFICE.

HENRY C. OSBORN, OF CLEVELAND, OHIO, ASSIGNOR TO AMSTUTZ-OSBORN CO., OF CLEVELAND, OHIO, A PARTNERSHIP.

LATHE-PAN DEVICE.

SPECIFICATION forming part of Letters Patent No. 697,413, dated April 8, 1902.

Application filed March 28, 1901. Serial No. 53,293. (No model.)

To all whom it may concern:

Be it known that I, HENRY C. OSBORN, a citizen of the United States, residing at Cleveland, in the county of Cuyahoga and State of Ohio, have invented new and useful Improvements in Lathe-Pan Devices, of which the following is a specification.

My invention relates to improvements in lathe-pan devices; and it consists of the features hereinafter described, and more especially pointed out in the annexed claims.

The object of this invention is to provide exchangeable pans for use under turning-lathes or other devices, so that quick exchanges can be made when different materials are being worked—as, for instance, the two most usually used materials requiring separation, iron and brass. Extra pans can be kept in reserve, so that kinds of materials 20 that are used infrequently may also have their chips separated.

With these ends in view I show such an instance of adaptation in the accompanying drawings as shall show the underlying features of my invention without in any way 25 limiting myself to the specific construction shown.

Figure 1 is an end elevation of a pair of pans in operative relation to each other, and 30 their change of position is shown by dotted lines. Fig. 2 is a side elevation of Fig. 1. Fig. 3 is a plan view of the locking-handle. Fig. 4 is a cross-section of one of the pans.

I use floor-standards A, which are tied together by angle-iron bars a, or they may be held in any other suitable manner. These tie bars or rods may, if desired, be made adjustable lengthwise thereof, so as to adapt the same standard A to more than two pans 40 and to different lengths of lathes. Ordinarily these rods would be made of standard lengths. The standards A may also be provided with any well-known forms of casters. As shown, their feet are slightly rounded on the under 45 side, so as to make it more easy to slide the pan-holding frame about.

Within vertical ways a' of the standards A adjustable bearing-pieces B are removably held by bolts a². For simplicity and cheapness of construction and positiveness of support the pieces B have formed therein a se-

ries of holes b, by means of which they are adjusted to different heights on the standards A. The upper ends of these pieces are bifurcated at b', so as to receive the trunnions c of the end pieces C. Joining the end pieces C are two rods D. These rods pass into holes d, formed in the pieces C, and they are held in place therein by clamping-bolts d'. By thus clamping the parts C and D together they are held as a unit, being free to rotate upon the trunnions c. Collars c' serve to hold the trunnions c and pieces B in assembled relation.

The lever B' is pivoted at the upper end of B. This lever has a short bifurcated end, which engages ribs c², and hereby holds the reel in a vertical position, and when the ribs c³ are engaged the reel is held horizontally, Fig. 3.

The pans E are formed of end castings e and a central semicylindrical trough or receptacle e', all being held together by tie-rods e². The castings e have handles E' and hooks e³, which pass over rods D, formed thereon. 75 If desired, eye-holes e⁴ may be cast on the end pieces e, so as to facilitate the removal of the pans by means of any suitable hand-hooks. On the under edge of the castings e drip-off projections are formed. The object of these 80 projections is to facilitate the dripping of oil from one pan into another and lastly into any kind of an oil-receptacle held on the tie-bars a. If desired, any suitable packing may be placed between the ends of the sheet-metal 85 trough e' and the grooved portion of the castings, into which the trough is placed, so as to hold the oil in the pan. The lower pair of ears for the tie-rods e² also serve as feet, upon 90 which the pan may rest when removed from the reel to the floor or bench.

What I claim is—

1. In lathe-pans, a removable frame, a removable member thereon, means for raising and lowering the same, and a revolute member in combination with removable receptacle supported by the revolute member, substantially as set forth.

2. In lathe-pans, in combination, a frame, end members rotatably mounted therein, rods connecting said end members, pans adapted to be suspended from said rods, one of said end

members having a longitudinal web and a handle pivoted to said frame and having a bifurcated part which may engage said web, substantially as set forth.

- 5 3. In lathe-pans, in combination, a trough adapted to be formed of sheet metal, end plates having grooves into which the ends of said trough fit, and tie-rods passing through said end plates, substantially as set forth.
- 10 4. In lathe-pans, in combination, a trough adapted to be formed of sheet metal, end plates having hooks, and tie-rods passing through said end plates and adapted to hold said trough in position, substantially as set forth.
- 15 5. In lathe-pans, in combination, a trough adapted to be formed of sheet metal, end plates having grooves into which the ends of said trough fit, said end plates having ears 20 which project to a point lower than the bot-

tom of said trough, and tie-rods which pass through said ears, substantially as set forth.

6. In lathe-pans, the combination of a central trough portion, end plates having hand-openings formed therein and means for holding the parts in assembled relation, substantially as set forth. 25

7. In lathe-pans, the combination of a central trough portion, end plates having drip projections formed thereon, and means for holding the parts in assembled relation, substantially as set forth. 30

In testimony whereof I have signed my name to this specification in the presence of two subscribing witnesses.

HENRY C. OSBORN.
